METHODS OF PREPARING STANNOUS PYROPHOSPHATE

Robert J. Gemmell, Brentwood, and George Douglas Nelson, St. Louis, Mo., assignors to Monsanto Chemical Company, St. Louis, Mo., a corporation of Delaware
No Drawing. Filed May 25, 1956, Ser. No. 587,195
2 Claims. (Cl. 23—105)

This invention relates to methods for making stannous pyrophosphate. Stannous pyrophosphate has been found to be suitable for use as a dentifrice polishing agent, and when produced in accordance with this invention provides a dentifrice base characterized by desirable properties such as opacity, freedom from a gritty feeling in the mouth, low glycerine absorption, and suitable polishing power.

It is an object of the invention to provide methods for preparation of stannous pyrophosphate which are superior to previously-known methods and which produce a pyrophosphate having the above desirable properties.

It is now well known that the application of certain soluble fluorides in restricted amounts to the teeth prevents or retards the development of dental caries. One way in which the fluorides are applied to the teeth is by incorporation into dentifrice cleansing and polishing compositions, such as tooth pastes and tooth powders. Tooth pastes and powders contain substantial amounts of polishing agents. These polishing agents must be carefully selected and controlled from the point of view of hardness, so that normal use of such pastes or powders will not cause undue tooth injury by severe abrasion.

Various phosphates, such as orthophosphates, are presently widely used as polishing agents in dentifrice cleansing compositions. However, if an orthophosphate, such as dicalcium orthophosphate, is utilized in a dentifrice composition containing a soluble fluoride salt, the fluoride anion will react with the orthophosphate to form an insoluble fluorapatite and/or calcium fluoride, thereby destroying the availability and effectiveness of the fluoride for the prevention of dental caries.

When certain soluble fluoride salts such as tin fluoride are used in dentifrice formulations, it has been found that the metallic cation has a synergistic effect on the action of the fluoride in inhibiting tooth decay. However, when an orthophosphate is used as a polishing agent, the metallic cation is precipitated as an insoluble metal phosphate. By use of the stannous pyrophosphate of the present invention, both of the above types of precipitation are markedly retarded in fluoride dentifrices.

Stannous pyrophosphate may be used as a dentifrice base, alone or with other fluoride compatible polishing agents, such as calcium pyrophosphate or insoluble sodium metaphosphate. The said group of compounds provides for the presence of pyrophosphate in a form which avoids the above-described disadvantage of the prior art compounds. At the same time stannous pyrophosphate is characterized by low abrasion, which is an important property in the formulated dentifrice.

Stannous pyrophosphate prepared in accordance with the present invention is essentially insoluble in water, and is characterized by the presence of little or no orthophosphate. The method of preparation of the present invention is the reaction of sodium acid pyrophosphate with stannous chloride. The reaction is conducted in an aqueous medium, so that it is desirable to provide solutions, slurries or suspensions of the starting materials in water.

In accordance with the present invention, there is added to a slurry or aqueous solution of stannous chloride a solution of sodium acid pyrophosphate. The stannous pyrophosphate is reacted in stoichiometric proportion, although an excess thereof may be employed if de-

2

sired. The reaction is conducted in a mixing vessel provided with agitation means such as a shaft stirrer or propeller. A preferred temperature range is from 35° C. to 100° C., which is maintained until conversion is substantially complete in the production of the insoluble stannous pyrophosphate. In order to achieve complete precipitation it is desirable to neutralize the solution with a base such as NaOH or Na₂CO₃ to produce normal pyrophosphate salts. The metal pyrophosphate thus obtained may be the anhydrous form, particularly as the result of prolonged heating. A preferred reaction time is from 0.5 to 30 hours. The reaction mixture containing a slurry of the insoluble stannous pyrophosphate and soluble sodium salts is then filtered to remove the soluble salts and to obtain the desired stannous pyrophosphate as the residual product. The dry product is ground to the desired fineness for dentifrice purposes, such as —375 mesh particles.

The "hardness," "polishing power" or "abrasion" of the stannous pyrophosphate of the present invention may be expressed in terms of a convenient numerical scale as described below. The pyrophosphate polishing agent, which has been the preferred polishing agent in the past, i.e., calcium pyrophosphate, generally had a polishing power of between 30 and about 40, although in a few isolated instances, material might have been obtained having a polishing power as low as about 25. In contrast thereto, the pyrophosphate of the present invention can have a polishing power of about 5. The range of polishing power or abrasion values which may be obtained generally run between about 3 and 30. The preferred range of hardness or polishing power of the said pyrophosphate for use in fluorine-containing dentifrice compositions is between about 10 and about 25.

The following method is used for determining the polishing power of the pyrophosphate produced in accordance with the present invention.

The method is based on the weight of metal abraded from an electrolytic copper strip by brushing with a tooth brush having natural bristles under standard conditions in a glycerine suspension of the abrasive to be tested. A clean copper strip is rinsed with alcohol, dried in an oven at 60° C., cooled in a desiccator, weighed, and inserted into a suitable holder, which is located in a trough. The tooth brush is attached to a reciprocating holder, moistened, and then lowered against the copper strip, the brush being adjusted so that it touches the copper strip along the entire length of the brush. Once this has been achieved, the brush is rigidly fixed in position. The sample to be tested is prepared by weighing 20 g. of the powdered material into a 150 ml. beaker and then adding and mixing in a 50% aqueous glycerine solution until the resulting paste flows readily upon tilting the beaker. The paste thus prepared is poured into the above trough and the brush lowered into contact with the copper strip. The brush holder is reciprocated 14,400 times in about 120 to 123 minutes, so that including the forward and reverse motions of the brush, a total of 28,800 strokes are applied to the copper strip.

At the end of the foregoing operation, the copper strip is removed, washed with water, and then with ethyl alcohol. The washed strip is then dried for five minutes at 60° C., cooled in a desiccator, and reweighed. The loss in weight in milligrams represents the polishing power. Thus, if the copper strip loses 10 mg. in weight, the abrasive material being tested is said to have a polishing power of 10.

The following examples illustrate specific embodiments of the invention:

Example 1

The preparation of stannous pyrophosphate was car-

ried out by dissolving 1,125 g. of stannous chloride dihydrate in 800 ml. of 19% hydrogen chloride solution at 60° C. To this mixture there was added a solution of 600 g. of sodium acid pyrophosphate (5% excess) and 3,000 ml. of water at 60° C. At the completion of the addition, the hydrogen chloride was neutralized by the addition of sodium carbonate, resulting in the complete precipitation of the desired stannous pyrophosphate. The precipitate was then filtered, washed, dried and ground.

The physical and chemical properties of the stannous pyrophosphate were as follows:

SnO	percent	66.8
P ₂ O ₅	do	29.6
Moisture	do	0.33
pH	do	4.2

Screen analysis:

Cumulative retained 200	do	0.05
Cumulative retained 325	do	2.33
Abrasion value		24.6
Glycerin absorption value		42.0

The above pyrophosphate is particularly desirable in the formulation of tooth paste, because of its high opacifying power. The use of the said pyrophosphate in a glycerine-containing tooth paste based on insoluble sodium metaphosphate is found to yield a product having a dense white color and opacity, making it unnecessary to use any additional opacifying agent in the formulation.

Stannous pyrophosphate employed as dental polishing agent is also useful for its cleansing and stain-removing action. In addition, the stannous pyrophosphate does not produce an unpleasant taste or feel in the mouth.

In the compounding of tooth pastes it is preferred to employ about 40% to 60% by weight of the dry base, which base may then be combined with varying percentages of glycerine, gums, water, flavoring materials, etc. In addition, there may be incorporated various wetting, emulsifying or foaming agents, such as the sodium alkyl sulfates. In the preparation of tooth powders, it is preferred to employ the above-described stannous pyrophosphate in amount varying from 36%-97% by weight of the final product, but a broader range of 1-97% to include smaller proportions may be used, particularly if other dentifrice bases are introduced into the formulation. Other dentifrice bases which may be employed, together with products made by the present invention are magnesium pyrophosphate, calcium pyrophosphate and insoluble sodium metaphosphate.

The compositions embodying the present invention, when used in a dentifrice formulation in paste or powdered form, are capable of cleaning and polishing the teeth and of restoring and maintaining their natural lustre without abrading or scratching the surfaces of the teeth. Moreover, the combination with fluorides provides a novel and efficient means of uniformly supplying controlled amounts of fluoride to the teeth with the ultimate result of preventing and controlling dental caries.

In the preparation of fluorinated dentifrices utilizing the above-described stannous pyrophosphate the fluoride

content may be provided by the use of a soluble fluoride salt, such as stannous fluoride, sodium fluoride, potassium fluoride, ammonium fluoride, etc., which provide the fluoride ion in the dentifrice composition. If it is desired to utilize calcium pyrophosphate and/or insoluble metaphosphate as an additional phosphate component, these materials also may be introduced into the dentifrice formulation. The above components are employed in substantially the proportion set forth below, representative 10 of an example of the present invention.

Example 2

A tooth powder was prepared utilizing the following formulation by weight, and also indicating the range of 15 variation of the components. This formulation may also be employed without the fluoride as a general dentifrice.

	Component	Weight, grams	Range, percent
20	Stannous pyrophosphate	21	1-97
	Calcium pyrophosphate	400	1-97
	Sodium fluoride	0.45	0.01-0.50
	Detergent (sodium lauryl sulfate)	20	2-8
	Saccharin	1	0.05-2
	Flavoring (essential oil)	4	0.05-2
25		450	

What is claimed is:

1. A process which comprises bringing together under reactive conditions stannous chloride and at least a stoichiometric quantity of sodium acid pyrophosphate to effect reaction between said stannous chloride and a stoichiometric quantity of said sodium acid pyrophosphate, whereby stannous pyrophosphate is produced.
- 35 2. Process for the preparation of stannous pyrophosphate which comprises reacting an acidic solution of stannous chloride with a stoichiometric quantity of sodium acid pyrophosphate and thereafter neutralizing the solution with a basic substance selected from the group consisting of sodium carbonate and sodium hydroxide, whereby a precipitate of stannous pyrophosphate is obtained.
